WINDOW RAISING MECHANISM

Filed March 24, 1928

INVENTOR:
Raymond J. Hansen,
BY Fred W. Hansen
ATTORNEY

UNITED STATES PATENT OFFICE

RAYMOND J. HANSEN, OF REDONDO BEACH, CALIFORNIA

WINDOW-RAISING MECHANISM

Application filed March 24, 1928. Serial No. 264,315.

My invention relates to window-operating devices, and more particularly to a novel operating mechanism for automobile windows.

The common method of raising and lowering a glass window in an enclosed automobile comprises a crank which operates through a reducing gear or worm to lower or raise the window, the direction of rotation of the crank determining the direction of travel of the window. Such a crank is ordinarily unavoidably located in such a position that it is impossible for the person seated next to the window to raise or lower the glass without turning in the seat in order to get a better grip, and secure sufficient leverage, to operate the crank. Besides being inconvenient to operate, such a crank often catches in the clothing when a person is leaving or entering the vehicle. My window-raising mechanism provides a handle which is conveniently located adjacent the glass and in a position in front of the operator. In raising or lowering the window, the operator moves the handle toward or away from him, this pumping action moving the glass window through a predetermined cycle of opening and closing operations.

It is an object of my invention to provide a window-raising mechanism operable by moving a handle with a pumping motion, this movement being transmitted to a window.

In accomplishing these results, I provide a ratchet gear which is connected to the window through a suitable crank mechanism, this ratchet gear being, in turn, rotated by any reciprocation of the handle in a manner to move the window through a predetermined cycle.

It is an object of my invention to provide a window-raising mechanism which is actuated by the reciprocation of a lever to draw the window through a predetermined cycle.

It is another object of my invention to provide a window-operating mechanism having a reciprocable handle, the work done on one stroke of this handle being greater than the work done on the other stroke.

Still a further object of my invention is to provide a device for resiliently holding the

window in an extreme open and closed position.

Other objects of my invention lie in the provision of a novel operating mechanism for transferring reciprocating motion into circular motion.

Further objects and advantages of my invention will be made evident hereinafter.

In the drawing, I have illustrated my invention as applicable to an automobile door without limiting myself thereto.

Referring to the drawing,—

Fig. 1 is a view illustrating a portion of an automobile body equipped with my invention.

Fig. 2 is a view showing the details of my invention.

Fig. 3 is a cross-sectional view taken on the line 3—3 of Fig. 2.

Referring particularly to Fig. 1, I illustrate an automobile body 10 having a door 11 therein, this door operating on hinges 12. This door has an opening 13 which may be entirely closed by a glass 14, this glass being adapted to be lowered in the door 11 into a position indicated by the numeral 15 of Fig. 1 at the will of the operator.

The mechanism for accomplishing this raising and lowering of the glass 14 is best illustrated in Figs. 2 and 3.

Referring to these figures, I illustrate the door 11 as comprising an outer plate 17, forming the outer surface of the door, and an inner plate 18, these plates being closed at their upper ends by a plate 19. Secured in the door 11 is a suitable supporting structure 20 which may conveniently be the structure bracing the door 11. I have shown this structure as comprising an end sill 21 having a side member 22. Secured to the inner edge of this side member as by screws 23 is a supporting plate 24 to which a pivot member 25 is attached by bolts 26. This pivot member has a bearing member 27 which journals a shaft 28. To the outer end of this shaft is connected an arm 30. On the outer end of this arm is pivoted a roller 31 which fits into a horizontal channel 32 of a glass-attaching member 33. The glass 14 is secured to the upper end of this glass-attaching member 33 by any suitable means,

this means being illustrated as a dovetail 35 in the member 33, this dovetail securely holding the lower end of the glass 14. Thus by raising and lowering the arm 30, the glass 14 5 may be raised and lowered in guides 36 provided by the door 11. The horizontal channel 32 of the glass-attaching member 33 is 10 suitably elongated so as to permit this vertical movement of the glass while the roller 31 is moving through an arcuate path. When the glass 14 is in an upper or closed position, the arm 30 assumes a position indicated by 15 dotted lines 37 of Fig. 2.

A suitable crank mechanism is provided to 20 thus oscillate the arm in order to move the glass 14 from open to closed position and vice versa. This mechanism comprises a link 40 pivoted to the arm 30, as indicated by the numeral 41, the upper end of this link being pivoted 25 on a pin 43 attached to a ratchet gear 45 which is, in turn, journalled on a shaft 46, this shaft being secured to an element 47 which is bolted to the supporting structure. The distance 30 between the pin 43 and the shaft 46 is so proportioned that one complete revolution of the ratchet gear 45 will move the glass 14 through a complete raising and lowering operation. In other words, when the ratchet gear 45 is rotated, the glass 14 moves through 35 a complete cycle each time the ratchet gear has made one complete revolution.

The ratchet gear 45 has teeth 50 thereon, these teeth being pointed at their extremities, 40 as indicated in Fig. 2. Adapted to rotate the ratchet gear 45 in a direction indicated by the arrow 51, is a pair of advancing members which, for convenience, I have termed primary and secondary advancing members 53 and 54, respectively. These advancing members 45 are operated by a handle 55 extending through an opening 56 in the upper plate 19 so as to be moved by the operator. As best 50 shown in Fig. 2, the primary and secondary advancing members 53 and 54 are respectively pivoted on pins 58 and 59 carried by the handle 55. The handle 55 is, in turn, pivoted to the element 47 by means of a trunnion 60. The primary and secondary advancing members 55 have engagers 61 and 62 formed thereon, these engagers being of a shape indicated in Fig. 2. A spring 63 operates between the advancing members 53 and 54 to maintain the engagers 61 and 62 in contact with the teeth 50 of the ratchet gear 45.

The primary and secondary advancing members 53 and 54 are effective in rotating the ratchet gear 45. Thus, when the mechanism is in its full line position indicated in Fig. 2, and the operator moves the handle 55 in a direction indicated by the arrow 69, the secondary advancing member 54 moves leftward, the engager 62 thereof meshing with the teeth 50 to turn the ratchet gear in a direction indicated by the arrow 51. When the handle 55 has been moved into an extreme for-

ward position, indicated by the numeral 70, the secondary advancing member will have assumed a position indicated by the numeral 71. During this forward movement of the handle 55, the primary advancing member 53 70 has skipped over a plurality of teeth and now lies in a position indicated by the numeral 73. When the operator again draws the handle 55 rearward, in a direction indicated by the numeral 75, the engager 61 of the primary advancing member engages the teeth of the ratchet gear and moves this gear in a direction indicated by the arrow 51. During this rearward movement of the handle 55, the secondary advancing member skips over a plurality of teeth into its full line position shown 80 in Fig. 2. Thus, the oscillations of the handle 55 are transmitted into a rotary motion of the ratchet gear 45, this gear forming a portion of the crank mechanism which moves the 85 glass 14 through its continuous cycle.

In order to counter-balance the weight of the glass 14, I provide a tension spring 80, one end of which is secured to the sill 21 and the other end of which is secured to the arm 30. Thus, the only force required to raise and lower the window is that due to the friction of the glass in the guides 36. It should thus be apparent that the energy required to oscillate the handle 55 is very small. Inasmuch as the handle 55 is positioned in the forward end of the door 11, it is at all times within convenient reach of the operator, and the pumping action required when moving the handle 55 is almost directly toward and 95 away from the operator.

An operator may invariably exert more force in pulling the handle 55 toward him, in a direction indicated by the arrow 75, than he does in pushing the handle 55 away from him, in a direction indicated by the arrow 69. Due to this fact, the greater amount of work performed in raising or lowering the window should come on the rearward stroke; in other words, when the handle 55 is being 100 moved in the direction of the arrow 75. This I accomplish by forming the pin 58 on the handle 55 a greater distance from the trunnion 60 than is the pin 59. Thus, for a given 105 angular movement of the handle 55, the pin 58 will travel a correspondingly greater distance than the pin 59, and the engager 61 will thus turn the ratchet gear 45 a greater angular distance than will the engager 62. The 110 leverage obtained by the action of the primary advancing member is thus different from that obtained by the secondary advancing member, the greater amount of work being done when the handle 55 is moved in the direction of the arrow 75.

In order to resiliently hold the glass 14 in an extreme upper or lower position, I provide a lug 81 slidable in a member 82 of the element 47, this lug being pointed and spring-actuated to urge it in a direction toward the 115 120 125 130

ratchet gear 45. This ratchet gear is provided with diagonally opposite depressions 84 in which the lug 81 is pressed when either of the openings 84 is aligned therewith. The openings 84 are so positioned that one of these openings will be engaged by the lug when the glass 14 is in an uppermost position and the other will be engaged when the glass is in a lowermost position. The point of the lug 81 is so designed that it will resiliently hold the glass 14 in an extreme upper or lower position, but the ratchet gear 45 may be easily turned to release the lug 81 from the opening 84 in which it is seated. This releasing action is further aided by the peculiar linkage of the ratchet gear 45 and the link 40, this linkage moving the glass 14 at an increasingly slower rate as this glass nears its upper or lower position. This slower movement as the glass nears its extreme positions also aids in permitting an easy engagement of the lug and the openings 84, and the increased leverage obtainable in these positions makes the withdrawal of the lug from the openings an easy matter.

I claim as my invention:

1. In a window-moving mechanism, the combination of: a glass; a crank mechanism operatively connected to said glass to move said glass through a complete cycle; and reciprocable means for rotating said crank mechanism in a given direction, said rotation moving said glass through said cycle.

2. In a window-moving mechanism, the combination of: a supporting structure; a glass movable in said supporting structure; a ratchet gear pivoted to said structure; means connecting said ratchet gear and said glass, said means moving said glass through a complete cycle when said ratchet gear makes one revolution; and reciprocable means for rotating said ratchet gear.

3. In a window-moving mechanism, the combination of: a supporting structure; a glass movable in said supporting structure; a ratchet gear pivoted to said structure; means connecting said ratchet gear and said glass, said means moving said glass through a complete cycle when said ratchet gear makes one revolution; and means for unidirectionally rotating said ratchet gear.

4. A combination as defined in claim 1 in which said means for rotating said crank mechanism includes a reciprocable handle.

5. A combination as defined in claim 2 in which said means for rotating said ratchet gear includes a reciprocable handle.

6. In a window-moving mechanism, the combination of: a glass; a crank mechanism operatively connected to said glass to move said glass through a complete cycle; reciprocable means for rotating said crank mechanism in a given direction, said rotation moving said glass through said cycle; and means for resiliently holding said glass in

positions at the extremities of its cycle.

7. In a window-moving mechanism, the combination of: a supporting structure; a glass movable in said supporting structure; a ratchet gear pivoted to said structure; means connecting said ratchet gear and said glass, said means moving said glass through a complete cycle when said ratchet gear makes one revolution; reciprocable means for rotating said ratchet gear; and means for resiliently holding said glass in positions at the extremities of its cycle.

8. In a window-moving mechanism, the combination of: a supporting structure; a glass movable in said supporting structure; a ratchet gear pivoted to said structure; means connecting said ratchet gear and said glass, said means moving said glass through a complete cycle when said ratchet gear makes one revolution; a reciprocable handle pivoted to said supporting structure; and an advancing member operatively connecting said ratchet gear and said handle.

9. In a window-moving mechanism, the combination of: a supporting structure; a glass movable in said supporting structure; a ratchet gear pivoted to said structure; means connecting said ratchet gear and said glass, said means moving said glass through a complete cycle when said ratchet gear makes one revolution; a reciprocable handle pivoted to said supporting structure; and an advancing member operatively connecting said ratchet gear and said handle, said handle and said advancing member cooperating to rotate said ratchet gear in a single direction.

10. In a window-moving mechanism, the combination of: a supporting structure; a glass movable in said supporting structure; a ratchet gear pivoted to said structure; means connecting said ratchet gear and said glass, said means moving said glass through a complete cycle when said ratchet gear makes one revolution; a reciprocable handle pivoted to said supporting structure; and a pair of advancing members pivoted to said handle and engaging said ratchet gear, said advancing members cooperating to change any reciprocatory motion of said handle into a uni-directional rotation of said ratchet gear.

11. A combination as defined in claim 10 in which the leverage of said advancing members is unequal.

12. In a window-moving mechanism, the combination of: a supporting structure; a glass movable in said supporting structure; a ratchet gear pivoted to said structure; means connecting said ratchet gear and said glass, said means moving said glass through a complete cycle when said ratchet gear makes one revolution; a reciprocable handle pivoted to said supporting structure; a pair of advancing members pivoted to said handle and engaging said ratchet gear, said advancing

ing members cooperating to change any reciprocatory motion of said handle into a unidirectional rotation of said ratchet gear; and means for pressurally holding said advancing members in contact with said ratchet gear.

13. In a window-moving mechanism for an automobile window, the combination of: a supporting structure; a glass movable in said supporting structure; a reciprocable handle pivoted to said supporting structure; and mechanism connecting said handle and said glass whereby any reciprocation of said handle causes a movement of said glass through a given opening and closing cycle.

14. In a window-moving mechanism, the combination of: a supporting structure; a glass slidable in said supporting structure; a glass-attaching member secured to said glass; an arm pivoted to said supporting structure and connected to said glass-attaching member; a ratchet gear pivoted to said supporting structure; a link connecting said ratchet gear and said arm whereby one complete revolution of said ratchet gear moves said glass through a complete raising and lowering cycle; and means adapted to be reciprocated for rotating said ratchet gear.

15. In a window-moving mechanism, the combination of: a supporting structure; a glass slidable in said supporting structure; a glass-attaching member secured to said glass; an arm pivoted to said supporting structure and connected to said glass-attaching member; a ratchet gear pivoted to said supporting structure; a link connecting said ratchet gear and said arm whereby one complete revolution of said ratchet gear moves said glass through a complete raising and lowering cycle; a reciprocable handle pivoted to said supporting structure; and a pair of advancing members pivoted to said handle and bearing against said ratchet gear.

In testimony whereof, I have hereunto set my hand at Los Angeles, California, this 19th day of March, 1928.

RAYMOND J. HANSEN.
